[57] **CLAIM**

The ornamental design for an adjustable length shaft for a
golf putter, as shown and described.

DESCRIPTION

FIG. 1 is an exploded right side elevational view of a golf
putter having an adjustable length shaft showing my new
design;

FIG. 2 is a right side elevational view;

FIG. 3 is a front elevational view of FIG. 2;

FIG. 4 is a rear elevational view of FIG. 2; and,

FIG. 5 is a perspective view of FIG. 2.

The broken line showing of a putter head and the human
figure are for illustrative purposes only and forms no part of
the claimed design.
